COMBINED BLOTTER AND CALENDAR HOLDER

Edward A. Quist, Pueblo, Colo.

Application May 29, 1953, Serial No. 25,244

Term of patent 14 years

(Cl. D74—1)

To all whom it may concern:

Be it known that I, Edward A. Quist, a citizen of the United States of America, residing at Pueblo, in the county of Pueblo and State of Colorado, have invented a new, original, and ornamental Design for a Combined Blotter and Calendar Holder, of which the following is a specification, reference being had to the accompanying drawing, forming a part thereof, wherein:

Figure 1 is a side elevational view of a combined blotter and calendar holder showing my new design;

the side opposite to that shown in Figure 1, and Figure 4 is an end view.

I claim:

The ornamental design for a combined blotter and calendar holder, as shown.
